UNITED STATES PATENT OFFICE.

FREDERICK J. MACNISH, OF OAK PARK, ILLINOIS, ASSIGNEE TO CREAMERY PACKAGE MANUFACTURING COMPANY, OF CHICAGO, ILLINOIS, A CORPORATION OF ILLINOIS.

PASTEURIZER.

1,023,323.

Specification of Letters Patent. Patented Apr. 16, 1912.

Application filed March 5, 1909. Serial No. 481,488.

To all whom it may concern:

Be it known that I, FREDERICK J. MACNISH, a citizen of the United States, residing at Oak Park, in the county of Cook and 5 State of Illinois, have invented certain new and useful Improvements in Pasteurizers, of which the following is a specification.

This invention relates particularly to apparatus used for pasteurizing milk and 10 cream.

One of the objects of this invention is to provide improved means for obtaining a constant and uniform circulation of the heating medium.

15 Another object of the invention is to improve the general construction of pasteurizers of the class indicated.

In the accompanying drawings, Figure 1 is a vertical central section through a pasteurizer embodying the features of my invention. Fig. 2 is a top plan view with the cover removed, and portions broken away. Fig. 3 is a detail illustrating the means for obtaining a circulation of the 25 heating medium.

The embodiment selected for illustration comprises a cylindrical casing consisting of a cylindrical wall 1 attached to a circular base 2, said base being, in this instance, supported upon legs 3. To the upper end of the cylindrical wall 1 is attached an annular casing-section 4. A bearing sleeve 5 is attached to the base 2 by suitable means, such as the nuts 6. A cylinder 7 is secured at its 25 lower end to a disk 8 on the sleeve 5, and at its upper end to an annular flange 9 upon the casing-section 4. It will be seen that the parts 1, 2, 4, 7 and 8 form a chamber 10 for the heating medium; the cylinder 7 and the disk 8 forming a chamber 11 for the milk or other liquid to be treated. The chamber 11 is closed by a suitable cover 12 adapted to make a tight joint with the annular flange 9, said cover being removably 40 secured in place by suitable means, such as a screw 13 carried by pivoted loops 14 and engaging lugs 15 on said cover.

A shaft 16 is rotatably mounted in the bearing sleeve 5, a collar 17 fixed on said 50 shaft being rotatably seated in a recess in the upper end of the sleeve. Upon the portion of the shaft 16 projecting above the upper end of the sleeve 5 are fixed arms 18 carrying two vertically extending vanes or blades 19, said blades being set at an angle

with the radius of the shaft 16 and extending into close proximity to the inner surface of the cylinder 7. The shaft 16 is rotated by suitable means, as, for example, a shaft 20 rotatably supported in bearings 21 and 22, and connected to the vertical shaft 16 by means of bevel gear wheels 23. Upon the horizontal shaft 20 is a tight and a loose pulley 24 and 25, respectively.

Steam is admitted to the chamber 10 for 65 heating water contained therein by means of a pipe 26 (Fig. 2) extending through the wall 1 and connecting with one end of a pipe 27 bent into the form of a nearly complete ring, the other end of said pipe 27 being closed by suitable means such as a cap 28. The ring 27, as herein shown, rests upon the base 2. A cylinder 29 is fixed at its lower end to the outer side of the ring 27 and extends upward to a suitable height 70 within the chamber 10. In the upper side of the ring 27 is a plurality of equidistant upwardly-extending nozzles 30, each surrounded by a nozzle or tube 31 of larger interior diameter and of greater height than 75 the nozzle 30, and secured to the ring 27. An opening 32 is formed in the cylinder 29 opposite each nozzle 30, said opening being continued through the adjacent side of the tube 31. 80

85 33 is an overflow pipe for the water resulting from condensation of the steam admitted through the pipe 26.

Milk or cream is admitted to the chamber 11 by suitable means, such as a pipe 34 having at one end a drain valve 35, the other end of said pipe extending upward through the base 2 and the disk 8 into communication with the chamber 11. A bowl or funnel 36 into which the milk may be poured or otherwise conducted is connected with the pipe 34 through the vertical standpipe 37. The heated milk leaves the upper end of the chamber 11 through the outlet pipe 38. 90

In operation, the steam escaping through 100 the nozzles 30 causes an upward movement of the water within the cylinder 29, the water in said cylinder flowing over the upper end of said cylinder and downward between the wall 1 and the cylinder 29 and 105 through the openings 32. It will thus be seen that the nozzles 30 produce a constant upward movement of heated water upon the outside of the cylinder 7. The milk admitted to the chamber 11 through the pipe 34 110

is thrown by the rapidly revolving vanes 19 outwardly against the inner surface of the cylinder 7, whereby all portions of the body of milk are uniformly heated to the desired 5 temperature, the milk rising until it reaches the upper end of the chamber 11 when it is discharged through the outlet pipe 38.

I would have it understood that I desire 10 not to be limited to the precise details of construction herein shown and described, for various modifications will occur to persons skilled in the art.

I claim as my invention:

1. In a pasteurizer, in combination, a milk 15 or cream container; a heating-medium container surrounding the first mentioned container; a partition surrounding said milk container within said heating-medium container; and inlet means for a heating medium 20 in the lower part of the heating-medium container at the inner side of said partition, said inlet means causing a circulation of the heating medium upwardly at the inner side of said partition and downwardly at the outer side thereof.
2. In a pasteurizer, in combination, a milk 25 or cream container; a heating-medium container surrounding the first mentioned container; inlet means for a heating medium comprising a series of nozzles in the lower 30 part of the heating-medium container and arranged around the first mentioned container; and a partition surrounding the first mentioned container, said nozzles being 35 located between said container and said partition, spaces being provided at the lower end of said partition for the passage of the heating medium from the outer side of said partition to the inner side thereof.
3. In a pasteurizer, in combination, a milk 40 or cream container; a heating-medium container surrounding the first mentioned container; inlet means for the heating medium comprising a coil in the lower part of the 45 second mentioned container and arranged around the first mentioned container; nozzles on said coil; and a partition attached to said coil, said nozzles being located between said partition and the milk or cream container, spaces being provided at the lower 50 end of said partition for the passage of the

heating medium from the outer side of said partition to the inner side thereof.

4. In a pasteurizer, in combination, a milk or cream container; a heating-medium container 55 surrounding the first mentioned container; inlet means for the heating medium comprising a coil in the lower part of the second mentioned container and arranged around the first mentioned container, said coil being arranged to discharge said heating medium at a plurality of points; a nozzle surrounding each of said discharge points; and a partition surrounding the milk or cream container and being located adjacent 60 to said coil, said partition having an opening therein opposite to and communicating with each of said nozzles.

5. In a pasteurizer, in combination, a milk or cream container; a heating-medium container 65 surrounding the first mentioned container; a partition in the heating-medium container surrounding the milk or cream container; and means located within the space bounded by said partition for heating 70 the heating medium, said partition being arranged to permit the flow of the heating medium from the outside of said partition to the inner side thereof.

6. In a pasteurizer, in combination, a cylindrical container for a heating medium; a cylindrical container for milk or cream, the second mentioned container being located within the first mentioned container; inlet and outlet means for the milk or cream container; inlet and outlet means for the heating-medium container; and a cylindrical partition in the first mentioned container surrounding the second mentioned container, the inlet means for the heating medium being 80 arranged to cause an upward movement of the heating medium in the space between the milk or cream container and said partition, spaces being provided at the lower 85 end of said partition for the passage of the heating medium from the outer side of said partition to the inner side thereof.

FREDERICK J. MACNISH.
